UNITED STATES PATENT OFFICE.

EDDY L. CLARK, OF PHILADELPHIA, PENNSYLVANIA, ASSIGNOR TO HIMSELF, JAMES M. GREGG, AND WILLIAM R. MURPHY, OF SAME PLACE.

DESIGN FOR A PAPER-WEIGHT.

SPECIFICATION forming part of Design No. 24,300, dated May 14, 1895.

Application filed May 13, 1893. Serial No. 474,147. Term of patent 14 years.

To all whom it may concern:

Be it known that I, EDDY L. CLARK, a citizen of the United States, residing in the city and county of Philadelphia and State of Pennsylvania, have invented and produced a new and original Design for a Paper-Weight, of which the following is a specification, reference being had to the accompanying drawings.

Figure 1 is a side view of my design, and Fig. 2 is a plan thereof.

The characteristic feature of the design is a bell having a base consisting of a horizontal platform surrounded by a series of upright posts and horizontal rails.

A is a bell, or representation thereof, suspended from a trestle *a* supported upon a horizontal platform *a'*.

B is a series of vertical posts with ball heads thereon, such posts being arranged at

intervals apart near the sides and ends of the platform.

C is a series of horizontal parallel rails fastened, or represented as fastened, to the posts by links *c*. Rising from the central post on one end of the platform is a yoke frame which supports a miniature or smaller bell D. The sides of the platform, near its respective ends are provided with steps similarly to a car, and the whole is similarly mounted upon ²⁵ *wheeled trucks*, as shown most clearly in the drawings. ³⁰

What I claim is—

The design for a paper weight substantially as shown and described.

EDDY L. CLARK.
